Primary Examiner — Alison M Ofstun

(57) **CLAIM**

The ornamental design for a lint remover as shown and described.

DESCRIPTION

FIG. 1 is a front view of the lint remover showing my new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is another perspective view thereof.

In the drawings, the broken lines illustrate portions of the article which form no part of the claimed design.
